UNITED STATES PATENT OFFICE.

JOHN A. LAMONT, OF GRANITE CITY, ILLINOIS, ASSIGNOR TO AMERICAN STEEL FOUNDRIES, OF NEW YORK, N. Y., A CORPORATION OF NEW JERSEY.

BUILT-UP SIDE FRAME.

1,151,693.

Specification of Letters Patent. Patented Aug. 31, 1915.

Application filed April 22, 1915. Serial No. 23,029.

To all whom it may concern:

Be it known that I, JOHN A. LAMONT, a citizen of the United States, and resident of Granite City, in the county of Madison and State of Illinois, have invented certain new and useful Improvements in Built-Up Side Frames, of which the following is a specification.

My invention relates to railway cars, and has particular reference to a novel built-up side frame for use in connection with car trucks.

An object in the construction of the present device is to provide for economy in cost of construction. This economy is the result of the use of commercial rolled sections which are fabricated to form a substantially integral side frame structure.

A further object is to lessen the weight of such structures by so disposing the metal thereof that the greatest possible resistance is secured with minimum weight. In the present structure the principal parts of the truss, namely, the compression and tension members, are formed from commercial rolled shapes, the remainder of the parts being formed by casting in steel or malleable iron.

The invention will be more readily understood by reference to the accompanying drawings, wherein,

Figure 1 is an elevation of a portion of a car truck side frame constructed in accordance with my invention; Fig. 2 is a plan view of the same with a portion of the compression member broken away; Fig. 3 is a section on the line 3—3 of Fig. 1; Fig. 4 is a section on the line 4—4 of Fig. 1; Fig. 5 is a view similar to Fig. 1, showing a slightly modified construction; Fig. 6 is a plan view of the construction shown in Fig. 5, with the top arch bar removed; Fig. 7 is a longitudinal vertical section through the construction of Fig. 5, and, Fig. 8 is a section on the line 8—8 of Fig. 5.

Referring more particularly to Figs. 1 to 4, it will be seen that I provide a compression member 10, of channel form, and a tension member 11, of T-shape, both of these members being preferably commercial rolled shapes. Separating the columns 12, acting as struts. The ends of the truss are united by means of the casting 13, which acts also to hold a journal box 14.

The compression member 10, is connected to the columns 12, by means of rivets 14, the columns providing guides 15, for a bolster and having an enlarged portion 16, within which a bolster having lips or side guides may be inserted. At the ends the compression member abuts against a shoulder 17, formed on the casting 13, and in order to insure a rigid connection I provide side grooves or recesses 18, in the casting near the top thereof, the flanges 19, of the channel being bent into these recesses, as best shown in Fig. 3. The tension member 11, is fitted into a recess in the casting 13, as best shown in Figs. 1 and 4. The side flange 20, of the T, is terminated at the point 21, the web of the T being bent at or about the point of termination of the flange to lie in the plane of the web of the channel 10, as indicated at 22. Rivets 23, are passed through the compression and tension members and casting and serve to hold the parts rigidly together. The casting is provided with suitable pedestal jaws 24, between which the journal box 14, is held. A brace or filler 25, extends between the converging ends of the compression and tension members and rivets 26, unite these members to the web of the compression member.

In the construction of Figs. 5 and 6, the compression member 27, is of channel form but is not crimped or bent into engagement with the casting, merely abutting against a shoulder 28, formed thereon, the flanges of the channel being sheared off to lie in the plane of the top of the journal box 29, which is integral with the casting 30. The tension member 31, is of T-shape, the flange of the T, terminating at 32. The web 33, of the T, continues over the top of the box and terminates at the point 34. Rivets 35, extend through the two members and the box and unite the parts rigidly. The strut or columns 36, coöperate with the rolled shapes, the upper portion 37, being in the form of a channel and fitting within the channel of the compression member 37. The lower portion of the casting forming the columns is slotted to accommodate the flange of the T 31, as best shown in Fig. 7. As in the construction heretofore described, I provide an integral extension or brace 38, which lies at the junction of the top and bottom arch bars. In the form just described, the journal box is integral with the casting 30, this being 110

2
an alternative form for the construction shown in Figs. 1 to 4.

It will be understood that wherever I have referred to the use of rolled shapes that pressed shapes might be used with equal facility and that therefore I consider the terms rolled and pressed as synonymous.

I claim:

1. In a side frame, the combination of top 10 and bottom arch bars composed of rolled or pressed shapes, and a casting at the ends of said bars, said casting including downward projections acting as pedestal jaws and provided with a diagonally extending 15 recess, the arch bar composing the tension member being bent into the plane of the bar composing the compression member at the ends of the two members and occupying the recess in said casting, the parts being rigidly 20 united to form a substantially integral structure, substantially as described.
2. In a side frame, the combination of top 25 and bottom members and a strut, said top member being in the form of a channel, said bottom member being a rolled commercial flanged section, a flange of said bottom member being terminated at the point of junction with said top member, the web of said bottom member being bent into the plane of 30 said top member, and a casting with which said top and bottom members coöperate and to which they are rigidly secured, substantially as described.
3. In a side frame, the combination of top 35 and bottom members, said top member being

of channel shape and said bottom member being a commercial rolled shape, said bottom member being bent at its ends into the plane of said top member, a casting with which said members coöperate at their ends, 40 said casting having a recess and said top member being bent laterally into an engagement with said recess, substantially as described.

4. In a side frame, the combination of a 45 channel compression member and T-shaped tension member, the members being brought into engagement at their ends, and a casting having an integral portion lying between said tension and compression members at a 50 point adjacent to the junction of the two members, substantially as described.

5. In a side frame, the combination of compression member, tension member and strut, said compression member being of 55 rolled channel shape and said tension member of rolled T-shape, a casting with which said members coöperate at their ends, said casting having a T-shaped slot within which said tension member is accommodated, and a 60 shoulder against which said compression member abuts, said casting also being provided with a brace located adjacent to the junction of said tension and compression members and adapted to stiffen the same, 65 substantially as described.

JOHN A. LAMONT.
